UNITED STATES PATENT OFFICE.

ISAAC HICKS, OF HARTFORD, WISCONSIN, ASSIGNOR TO HIMSELF AND
LEWIS E. PECK, OF SAME PLACE.

IMPROVEMENT IN STUMP-EXTRACTORS.

Specification forming part of Letters Patent No. 36,585, dated September 30, 1862.

To all whom it may concern:

Be it known that I, ISAAC HICKS, of Hartford, in the county of Washington and State of Wisconsin, have invented a new and Improved Machine for Extracting Stumps; and I do hereby declare that the following is a full, clear, and exact description of the same, reference being had to the accompanying drawings, making a part of this specification, in which—

Figure 1 is a side sectional view of my invention, taken in the line *x x*, Fig. 2. Fig. 2 is a plan or top view of the same.

Similar letters of reference indicate corresponding parts in the two figures.

The object of this invention is to obtain a simple and efficient device for extracting stumps from the earth—one that may be operated with facility and readily moved from place to place in order to be applied to its work.

To this end the invention consists in the employment or use of two levers, or, rather, a compound lever, in connection with a lifting-bar and a fulcrum-supporting bar, all applied to a mounted frame and arranged as hereinafter fully shown and described.

The invention also consists in a novel arrangement or application of a back pair of wheels to the frame, whereby the latter, when the machine is to be used or applied to its work, may be made to rest upon the ground and the wheels and axle not allowed to be subjected to any strain or to sustain any weight while the machine is at work.

A represents a frame, which is composed of two parallel sill-pieces, *a a*, having each two uprights, *b b*, attached, the upper ends of which are connected by cross-bars *c c*. *B* is a bar, which is slightly inclined from a horizontal position, its front end being the lowest and resting upon the bolster *d* on the axle *e* of a pair of wheels, *f f*. The back end of the bar *B* rests upon the top of the frame *A*, and it is chamfered or beveled off at its upper surface and back end, as shown in Fig. 1 at *g*. In the upper surface of the bar *B* there is fitted a plate, *h*, which is at the inner end of the bevel *g* and forms the fulcrum of a lever, *C*, which is directly over the bar *B*, and is beveled at its under side directly over the bevel *g* of the bar *B*, as shown at *i* in Fig. 1. The bar *B* and lever *C* have slots *j* made through them at their bevel-

ed portions, and through these slots a lifting-bar, *D*, passes, and is retained by pins *k*, which will be presently described. In the bar *B* there is secured by a pin, *l*, the lower end of a perforated bar, *E*, which passes up through a mortise, *m*, in the lever *C*, and in the upper surface of the lever *C*, at its inner end, there is fitted a metal plate, *n*, which serves as a bearing for a lever, *F*, through which the perforated bar *E* also passes.

The operation is as follows: The lower end of the lifting-bar *D* is attached to the stump to be extracted and the short arm of the lever *C* is forced down and a pin, *k*, passed through the bar *D* in contact with the upper surface of the lever *C*. The inner end of the lever *F* is then forced down and a pin, *o*, passed through it in contact with the upper surface of lever *F*. The outer end of the lever *F* is then pressed down, and the pin *o* serves as a fulcrum for it. This movement of the lever forces down the inner end or longer arm of the lever *C*, and its shorter arm is of course elevated and the draw-bar *D* raised to a certain extent. In order to hold the lifting-bar, a pin, *o*, is passed through the bar *E*, directly over lever *C*, and a pin, *k*, is passed through a lifting-bar, *D*, directly over the bar *B*. The pin *k*, which passes through the bar *D* over lever *C*, is then withdrawn, and also the pin *o*, which passes through the bar *E* over the lever *C*. The short arm of lever *C* is then again forced down and a pin, *k*, passed through *D* above the short arm of lever *C*, and the inner end of the lever *F* is also forced down and a pin, *o*, passed through the bar *E* directly over *F*, which is again forced down at its outer end to actuate the lever *C* and further elevate the lifting-bar *D*. This operation of the levers *C F* is repeated until the stump is extracted. By this arrangement a single person may operate the machine, and each bar *D E* has two pins, *k k o o*, attached to it by a cord for the purpose of being passed through said bars.

If the two levers *C F* are not necessary, which may be the case in light work, the lever *C* only may be used. In either case the lever *C* may be retained or held at any point in its movement. The device is moved about from place to place on four wheels, one pair of which, *f f*, have been previously alluded to, and, being

arranged in a way common to all wheel-vehicles, do not require a minute description. The application, however, of the back wheels, G G, is peculiar, and forms an essential feature of the invention. The wheels G G are attached to an axle, H, which has a short perch or reach, I, connected to it, the front end of which is fitted on a guide-rod, J, which is at the under side of the bar B. The perch or reach I is allowed to slide freely back and forth on the rod J. (See Fig. 1.)

K K represent two levers, which are secured by fulcrum-pins p p in the back or outer uprights, b b, of the frame A. These levers pass through slots or mortises in the uprights b b and fit in grooves c c in the upper surface of the axle H of the wheels G G. To each lever K there is attached a hook, L, which extends downward.

When the machine is to be mounted in order to be drawn from place to place, the inner ends of the levers K K are depressed or forced down and the hooks L L are inserted in holes in the inner ends of the sill-pieces a a, as shown in Fig. 1, and the frame A will consequently be supported by the axle H, the axle bearing against the inner uprights, b b.

When the machine is to be applied to its work, the hooks L L are detached from the ends of the side pieces, a a, and the frame A is let down upon the ground. The raising and lowering of the frame A can be effected by one person.

This machine may be very cheaply constructed, and it contains no parts which are liable to get out of repair, and when repairing is necessary it can be performed by almost any one familiar with mechanics' tools.

Having thus described my invention, what I claim as new, and desire to secure by Letters Patent, is—

1. The combination of the bar B, levers C F, one or both, lifting-bar D, and fulcrum-supporting bar E, all arranged to operate as and for the purpose herein set forth.

2. The applying of the wheels G G to the frame A of the machine through the medium of the levers K K and hooks L L, arranged with the axle H and sill-pieces a a of the frame, as and for the purpose herein specified.

ISAAC HICKS.
